SPINDLE MOUNTING FOR TEXTILE MACHINES

William R. Gordon, Stonington, Conn., assignor
to The Atwood Machine Company, Stonington,
Conn., a corporation of New Jersey

Application August 31, 1937, Serial No. 161,801

6 Claims. (Cl. 118—66)

This invention relates to spindle constructions for textile machines and particularly to a swinging type spindle for yarn twisting machines.

A primary object of the invention is to provide 5 means to regulate the force holding the spindle toward its operative position with its whorl in contact with the spindle driving belt.

Another object of the invention is to provide an improved pivotal connection between the 10 swinging spindle mounting member and its supporting bracket, the swinging member also supporting an annular member on which may be detachably mounted a spindle enclosing member.

With the above and other objects in view the 15 invention includes the features of construction and operation set forth in the following specification and illustrated in the accompanying drawing.

In the accompanying drawing annexed hereto 20 and forming a part of this specification, I have shown the invention embodied in a standard form of twisting machine but it will be understood that the invention can be otherwise embodied and that the drawing is not to be construed as defining or limiting the scope of the 25 invention, the claims appended to this specification being relied upon for that purpose.

In the drawing:

Fig. 1 is a complete front elevation of a spindle 30 construction embodying my invention.

Figs. 2 and 3 are sectional views taken on the plane of line 2—2 of Fig. 1 and showing alternative constructions, and

Fig. 4 is a sectional view taken on the plane 35 of line 4—4 of Fig. 3.

In the above mentioned drawing there has been shown but one complete embodiment of the invention which is now deemed preferable, but it is to be understood that changes and modifications 40 may be made within the scope of the appended claims without departing from the spirit of the invention.

Briefly, and in its preferred aspect, the invention 45 may include the following principal parts: first, a supporting bracket secured directly to the frame tubes of the machine; second, a swinging member pivoted to said bracket; third, a spindle assembly mounted on the swinging member; fourth, a supporting ring or bracket for a spindle 50 enclosure mounted on said swinging member; fifth, a vertical pin or shaft forming the pivot for the swinging member; sixth, a spring disposed between the bracket and swinging member; and, seventh, securing means for the pivot pin enabling the pivot pin to be secured in any rotative 55

position so that the pressure of the swinging member toward its spindle driving position may be regulated.

Referring more in detail to the figures of the drawing there is shown one complete spindle assembly. It will be understood that a number of similar assemblies will be employed on a twisting machine spaced closely together. As each assembly is or may be identical, but one assembly is shown. A bracket 10 on which the spindle assembly is pivotally supported is rigidly secured to the frame tubes or pipe girts 11 of the machine. Any form of attachment permitting adjustment to accurately position the bracket and assembly 10 may be employed. As these securing or clamping means form no part of the present invention further description will not be necessary.

Secured to the bracket 10 in a manner presently to be more fully described is a vertical shaft 12 forming the pivot pin upon which a swinging member 13 may be mounted for limited angular movement. The shaft 12 is provided with spaced apart journal bearings engaging bearing surfaces provided in the swinging member 13.

On the swinging member 13 may be mounted a standard form of spindle assembly including a bolster 14 resiliently supported in position by a spring 15 and nut 16 in the usual manner. The spindle 17 and whorl 18 may be of any usual construction for the particular operations to be performed. As shown, the whorl 18 is adapted to contact with a wide flat driving belt 19 of standard form and maintained in contacting position by suitable idler pulleys 20.

The upper surface of the swinging member 13 is, as shown, horizontal and has secured thereto a ring or annular bracket 21 surrounding the spindle 17 and swinging with movements of the member 13. Mounted detachably within this ring or annular bracket 21 is a spindle enclosure 22 40 completely surrounding and enclosing the supply bobbin 23 and spindle 17. At the upper closed end of the enclosure 22 is a central aperture 24 through which the material being twisted may pass from bobbin 23 to the take-up means (not 45 shown).

To resiliently force the swinging member 13 toward its operative position to provide driving contact between the whorl 18 and belt 19, a helical spring 25 is disposed around the lower end of the shaft 12. The upper end of this spring 25 engages against a surface of the swinging member 13 and may have this end enter an aperture provided in the member 13. The lower end of the spring 25 is bent inwardly and enters a trans-

verse slot 26 provided in the lower end of shaft 12. Preferably and as shown there may be provided a spacing collar 27 secured to the shaft 12 which supports the weight of the swinging member 13 and parts mounted thereon.

In order to adjust the force exerted by the spring 25 against the swinging member 13 provision is made to secure the shaft 12 to its bracket in any angular or rotative position. The shaft 12 at an intermediate point is provided with an annular peripheral groove 28. A taper pin 29 within the bracket 10 passes across a portion of the groove 28 as shown in Fig. 2 and frictionally engages the shaft 12. A standard form of taper pin 29 entering a taper reamed hole in the bracket may be used, the frictional contact between the pin 29 and the surface of the shaft 12 being sufficient to securely retain the shaft 12 in adjusted angular position.

20 A cylindrical pin 30 as shown in Figs. 3 and 4 may be substituted for the taper pin 29. In this case the pin 30 would have one side bevelled off to form the desired taper and would preferably enter a cylindrical hole transversely of the bracket 10. The groove 31 shown in Fig. 4 for a pin such as shown at 30 may be so formed that the narrow plane surface of the pin 30 may engage the bottom surface of the groove 31.

To adjust the spring 25 to give the desired pressure of the whorl 18 against its driving belt 19 the parts may be assembled as shown with pin 29 or 30 lightly engaging the groove 28 or 31. With the parts so assembled and with a suitable tool inserted within slot 26 the shaft 12 is turned 35 to a position giving the desired pressure of the spindle assembly toward its operative position. The pin 29 or 30 then is tightly driven within its hole in the bracket 10 while the shaft 12 is in adjusted position so that a firm engagement takes 40 place sufficient to permanently retain the shaft 12 in adjusted position. With the shaft 12 so adjusted any desired force of the spring 25 may be used to provide the driving contact for rotating the spindle 17. As the shaft 12 can be secured in any angular position the pressure of the 45 spring 25 can be regulated very accurately. Also by simply loosening or removing the pin 29 or 30 to disengage the shaft 12 the shaft can be adjusted to a new position and secured therein.

50 It will be understood that the pins 29 or 30 can be inserted from either the front or rear of the bracket 10, whichever is most convenient and best adapted to retain the shaft 12 in its angularly adjusted and clamped position.

55 I claim as my invention:

1. A spindle mounting for textile machines comprising in combination a bracket, a shaft secured therein, a spindle mounting member pivotally supported on said shaft, a spring normally forcing the spindle mounting member toward its operative position, means to regulate said

spring by angular adjustment of said shaft relative to said bracket, and means to secure said shaft in said bracket in any pre-determined angular position.

2. A spindle mounting for textile machines comprising in combination, a bracket, a shaft secured therein, a spindle mounting member pivotally supported on said shaft, a spring surrounding said shaft and having one end contacting said spindle mounting member and the other end engaging said shaft, and means to secure said shaft in said bracket in any predetermined angular position, whereby the force of said spring against said member may be varied by angular adjustment of said shaft.

3. A spindle mounting for textile machines comprising in combination, a bracket, a shaft secured therein, a spindle mounting member pivotally supported on said shaft, a spring one end of which engages said shaft normally forcing the spindle mounting member toward its operative position, and frictional retaining means for said shaft in said bracket, whereby the angular position of said shaft and the pressure of said spring may be adjusted.

4. A spindle mounting for textile machines comprising in combination, a bracket, a shaft secured therein, a spindle mounting member pivotally supported on said shaft, a spring one end of which engages said shaft normally forcing the spindle mounting member toward its operative position, and a taper pin within said bracket frictionally engaging said shaft, whereby the angular position of said shaft and the pressure of said spring may be adjusted.

5. A spindle mounting for textile machines comprising in combination, a bracket, a shaft secured therein, a spindle mounting member pivotally supported on said shaft, a spring surrounding said shaft and having one end contacting said spindle mounting member and the other end engaging said shaft, frictional retaining means to secure said shaft in said bracket in any predetermined angular position, whereby the force of said spring against said member may be varied by angular adjustment of said shaft.

6. A spindle mounting for textile machines comprising in combination, a bracket, a shaft secured therein, a spindle mounting member pivotally supported on said shaft, a spring surrounding said shaft and having one end contacting said spindle mounting member and the other end engaging a slot formed in said shaft, and a taper pin extending through said bracket and frictionally engaging a groove in said shaft to secure said shaft in any predetermined angular position in said bracket, whereby the force of said spring against said member may be varied by angular adjustment of said shaft.

60 WILLIAM R. GORDON.
